UNITED STATES PATENT OFFICE

2,612,961

PROPELLER HAVING ADJUSTABLE BLADES

Cornelis Kapsenberg, Middelburg, Netherlands,
assignor to N. V. Koninklijke Maatschappij "De
Schelde," Vlissingen, Netherlands, a company
of the Netherlands

Application February 27, 1947, Serial No. 731,257
In the Netherlands March 9, 1943

Section 1, Public Law 690, August 8, 1946
Patent expires March 9, 1963

2 Claims. (Cl. 170—160.24)

1

The invention relates to a propeller for air- or watercraft comprising one or more pairs of diametrically disposed adjustable blades which can be actuated for adjustment from the craft, the said blades having crank-shaped root end portions supported in the propeller hub by means of trunnion members disposed at opposite ends of each of the crank-shaped portions, the actuating mechanism acting on the said crank-shaped portions.

It is another object of the invention to procure a construction which can be easily fitted together.

It is a further object of the invention to provide the crank-shaped portions with bearings at two points spaced apart in order to obtain a strong and stiff support for the propeller blades.

According to the invention each of the root ends of the blade is provided with two crank cheeks and with two bearing parts, the bearing parts of each blade root having different diameters, the bearing part of each root having the larger diameter being located at the side of the blade associated with the crank-shaped portion in question and bearing within the hub, whilst the bearing part of each blade root having the smaller diameter is supported for rotation within the larger bearing part of the other blade root.

As a result of the double bearing of each blade root large reaction moments may be taken up, so that large screw propellers can be made according to the invention.

Preferably the propeller blades are provided according to the invention with flange shaped feet and the bearing parts of the blade roots are made in the form of counter or thrust flanges therefor. Due to this construction a new blade can be fitted when the old one is broken, in just the same way as in an ordinary propeller, without removing anything from the hub or from the actuating mechanism or dismantling some other part of the propeller.

The construction according to the invention may be such as to enable the hub to be made in one piece (not in two halves for instance). The crankshaped blade root ends may be fitted through the radial hub borings and engage inside each other within the hub.

In the drawings:

Figure 1 is a cross sectional elevation of a propeller hub taken at right angles to the axis of the hub at the point where a pair of propeller blades are mounted in an adjustable manner on the hub.

Figure 2 illustrates in side view a hub for a four-bladed propeller.

Figure 3 is a side view of a propeller blade and its crank and trunnion.

Figure 4 is a sectional view of the hub.

In Fig. 1 the propeller hub is indicated by 1 and the blades 2 and 3 are diametrically arranged. The blade roots 4 and 5 include crank portions and are mutually of the same design. The portion 5 has a big bearing or shaft part 8 at the top constituting a trunnion which is rotatably mounted in a bearing in the periphery of the hub 1. At its lower end the portion 5 is provided with a smaller bearing or shaft part 9 bearing in the center of the big bearing part or trunnion 6 of the other crankshaped portion 4 of the other blades, which, in its turn, bears in the periphery of the hub 1. The small bearing part 7 at the free end of the crankshaped portion 4 bears in the big bearing part 8 of the portion 5.

The actuating mechanism engages the crank portions 4 and 5 at the places 10 and 11 formed as crank pins. The actuating rod is indicated by 14. The radial forces again are taken up by flanges 13 which are mounted separately. As shown in Fig. 3 the blades 3 are each provided with a flange-shaped foot 20 which is firmly attached by means of bolts 21 to the flange-shaped part 8.

In the case of propellers having more than one pair of blades, e. g. in the case of four-bladed propellers, the plane in which the second pair of blades will move may be arranged at some distance from the plane in which the first pair moves, as indicated in Fig. 2. In the case of three-bladed propellers each blade will move in another plane at right angles to the axis of rotation.

What I claim is:

1. A propeller comprising a hollow hub and a pair of blades diametrically protruding from said hub, the root ends of the blades extending into the hub and being crank-shaped within the space inside the hub, the portion of such root end between the blade and the crank-shaped portion being cylindrical in shape to constitute a trunnion, said hub having a cylindrical boring at the side of the blade serving as a bearing for said trunnion, said trunnion having a coaxial boring, the free end of the crank-shaped portion being provided with a cylindrical projection extending to the opposite side of the hub and coaxially with the said trunnion, said projection having a smaller diameter than the said trunnion, the said projection bearing in the coaxial boring of the trunnion that forms part of the other blade of the pair of blades with which the projection is coherent.

2. A propeller comprising a hollow hub and a pair of blades diametrically protruding from said hub, the blades being provided with flange shaped feet near the hub, such flange shaped foot of each blade being coaxially attached to a counter-flange-shaped member constituting a trunnion, said hub having a cylindrical boring in the circumference thereof serving as a bearing for said trunnion, the said trunnion having a coaxial boring and forming part of a crank-shaped member extending coaxially therewith into the hollow space inside the hub, the free end of the crank-shaped member being provided with a cylindrical projection extending to the opposite side of the hub and coaxially with the said trunnion, 10 said projection having a smaller diameter than the said trunnion, the said projection bearing in the coaxial boring of the counterflange-shaped

trunnion attached to the flange-shaped foot of the other blade of the pair of blades with which the projection is coherent.

CORNELIS KAPSENBERG.
